Patent expires January 7, 1964

6 Claims. (Cl. 123—62)

1

This invention relates to an internal combustion engine with double-acting crosshead scavenging pump.

Double-acting motor engines are known with double-acting crosshead-scavenging pumps. In the engines known of this kind, the crosshead guide forms a pumping cylinder, the crosshead guide being made cylindrical while at the same time the crosshead forms piston in the pump. In these known engines the crosshead guide or pumping cylinder contains the upper pumping chamber of the pump, while the lower pumping chamber is mainly made up of the crank case. In the known constructions there is consequently the very considerable drawback that the clearance in the lower end of the pump becomes very large, so that the efficiency of the lower pumping chamber becomes very small. The known construction furthermore has the drawback of being inapplicable in a modern Diesel engine with forced lubrication, as it will entail a very large waste of lubrication oil.

The purpose of this invention is to remedy the said drawbacks in engines with a cylindrical crosshead guide which forms a pumping cylinder, which contains the upper pumping chamber of the pump. The feature that is first and foremost peculiar to the invention is that the cylindrical crosshead guide, or in other words the pumping cylinder, besides containing the upper pumping chamber of the pump, contains furthermore the lower pumping chamber of the pump, which is separated from the crank case by a dividing wall—preferably a slide plate (in German: "Kulisse") movable in a horizontal guide and actuated by the connecting rod—through which in a way known per se the connecting rod is carried air-tight, and which permits the connecting rod to make its oscillating motion.

On account of the lower pumping chamber being separated from the crank case by said dividing wall, the pump may be constructed with very small clearance also in the lower pumping chamber. The efficiency in the two ends of the pump may therefore become equally good.

A slide plate movable in a horizontal guide, through which slide plate the connecting rod is carried air-tight, is known from single-acting petrol engines, in which the cylinder space under the working piston forms a pumping chamber,

2

which is separated from the crank case by a dividing wall made as such a movable slide plate. The said lower part of the cylinder space forms the pumping chamber in a single-acting charging pump.

The engine in accordance with the invention offers advantages through simple construction and simple and good mode of operation.

If the engine is single-acting the double-acting crosshead-scavenging pump offers the advantage that the diameter of the pumping piston will be smaller than would be the case, if the pump was single-acting. The crosshead will consequently become lighter, and the mass forces smaller. If the compressed air from both ends of the pump is led to a mutual pressure air pipe, a more uniform supply of air to the latter is attained than in a single-acting crosshead-scavenging pump.

In double-acting engines a uniform air supply to the two cylinder ends is likewise attained, as the air which is compressed on one side of the piston of the pump may be led direct to one cylinder end, i. e. either the upper or the lower working space of the cylinder, while the other working space is supplied with the air which is compressed on the other side of the pump piston.

Besides relating to a cylindrical crosshead guide or a pumping cylinder with pumping chambers with small clearances at both ends, the invention furthermore relates to various particulars in the engine with double-acting crosshead-scavenging pump here referred to:

In the accompanying drawing Figure 1 is a vertical central section through a double-acting internal combustion engine with a double-acting crosshead-scavenging pump in accordance with the invention. Figure 2 is an enlarged fragmentary detail in elevation showing the means for actuating the lower exhaust valve of the engine cylinder. Figure 3 is a sectional view taken at right angles to Figure 2.

Referring to the drawing in detail 1 is the upper cylinder end of the double-acting engine, and 2 the lower cylinder end. The piston is designated by 3, and the piston rod by 4. The latter is by a connection, e. g. by bolt or screws, which may be disconnected, connected to the crosshead 5. 6 is the connecting rod, and 7 the journal of a crank on the crank shaft 8. The cylindrical crosshead guide or the pumping

cylinder in the double-acting crosshead-scavenging pump is designated by 9, and the upper and lower suction valves or valve discs of the latter by 10 and 11, while the corresponding outlet valves or valve discs are designated by 12 and 13. The pressure air pipe 14 of the pump is in the embodiment shown mutual to both ends of the pump and delivers the pressure air to one or more scavenging ports 15 controlled by the piston 3, which ports are likewise mutual to the two cylinder ends 1 and 2.

The engine shown works with axial scavenging (i. e. scavenging in the longitudinal direction of the cylinder) at both ends and has exhaust disc valves 16 and 17 at top and bottom. The valve 16 is an ordinary disc valve, whereas the valve 17 is tubular and encloses the piston rod 4. The exhaust valve 16 in the upper cylinder end is closed by one or more springs 18 and is actuated for opening by means of a lever 19, which through a vertical rod 20 is moved by a cam 21 on a control shaft 22. The exhaust valve 17 in the lower cylinder end 2 is shown open. It is actuated for opening from the cam 21 through a vertical rod 23, which turns a preferably fork-shaped lever 24, which through two arms 25, actuates the valve 17. Below at either side of the piston rod 4 the valve 17 has a downwards-directed projection 30 in which there is a hole for a bolt 31. Correspondingly there are at the ends of the two fork branches 32 of the lever 24 two holes for bolts 33. The bolts 31 and 33 secure the two connection arms 25. The said arms 25 consist as shown in Fig. 3 separately of two connection links 34 secured by the bolts 31 and 33. This is actuated for closing by one or more springs 26. The pumping cylinder 9 in the crosshead pump is closed above by a cover 27 and below by a slide plate 28 movable in a horizontal guide, which slide plate is rotatably connected to the connecting rod 6 and is moved from the latter.

In the double-acting engine shown on the drawing the top or top cover 27 of the pump is so separated from the bottom cover of the working cylinder or the corresponding part, that in the bottom cover or part there may be fitted one or more valves, e. g. an exhaust valve 17, which in a way known per se is together with an exhaust valve 16 in the cylinder top controlled from a mutual control shaft 22.

In the embodiment shown is used axial scavenging away from the piston in both cylinder ends, but this is not necessary. Instead axial scavenging may be used down towards the piston at both ends, and the valves 16 and 17 will then be inlet valves, while the ports 15 become exhaust ports. The said ports 15 may both as inlet and exhaust ports be substituted by a single port or e. g. by two rows of ports situated above each other. Instead of a single inlet or exhaust valve there may at each cylinder end be used several valves.

A double-acting engine in accordance with the invention may also be constructed with transverse or return scavenging either at both cylinder ends or with axial scavenging at one cylinder end, e. g. the upper or the lower end, and with transverse or return scavenging or a similar scavenging at the other cylinder end.

Dependent on the engine being built in one way or the other, there is either as shown on the drawing used a single pressure air pipe 14 mutual to both ends of the pump, or separate pressure air pipes from each of the ends of the pump to the upper and lower cylinder ends 1 and 2 in the

engine, due regard being paid to attain a uniform supply of air to the pressure air pipe or pipes and the cylinder ends respectively.

The invention is not limited to double-acting engines, but comprises also single-acting engines with double-acting crosshead-scavenging pumps. In a single-acting engine there may also be used one or more piston-controlled scavenging ports in combination with an exhaust disc valve similar to the valve 16 on the drawing, so that the single-acting engine is mainly made to correspond to the double-acting engine shown on the drawing, when the lower cylinder end of the latter is out of the way. By leading the pressure air from both ends of the pump to a mutual pressure air pipe, a more uniform supply of air to the latter is attained than in a single-acting crosshead-scavenging pump.

A single-acting engine in accordance with the invention may also be made with axial scavenging down towards or away from the piston, or with transverse or return scavenging, just as explained with regard to a double acting engine. In a single-acting engine there may also be used one or more piston-controlled ports and one or more disc valves.

In accordance with the invention especially a double-acting engine may be made so as to be simple of construction and of a small building height. Cam-controlled inlet or exhaust valves are advantageously used in both covers or the corresponding parts of the cylinder, and piston-controlled ports at the middle of the latter. The engine requires no special camshaft 22, as the valve control e. g. may be effected from the crank shaft.

I claim:

1. In an internal combustion engine, an engine cylinder, a piston in the cylinder and having a piston rod, a pumping cylinder, a pump piston in the pump cylinder and connected with said rod, said pump piston and pump cylinder forming, respectively, a crosshead and guide and the pump cylinder having a pumping chamber on each side of the pump piston, a crank shaft, a connecting rod connecting the pump piston with the crank shaft, and a partition member receiving and participating in the oscillatory movement of the connecting rod and forming a closure for the adjacent end of the pump cylinder.
2. An internal combustion engine as claimed in claim 1 provided with a rotatable member forming a fluid tight joint between the connecting rod and the partition member.
3. An internal combustion engine as claimed in claim 1 provided guides movably receiving said partition member.
4. An internal combustion engine as claimed in claim 1 provided with exhaust valves in the opposite ends of the engine cylinder, and actuating means common to the several valves.

5. An internal combustion engine as claimed in claim 1 wherein the two pumping chambers of the pump cylinder are of substantially the same volumetric capacity.
6. In an internal combustion engine, an engine cylinder, a piston in the cylinder and having a piston rod, a pumping cylinder, a pump piston in the pump cylinder and connected with said rod, said pump piston and pump cylinder forming, respectively, a crosshead and guide and the pump cylinder having a pumping chamber on each side of the pump piston, the two pumping chambers of the pump cylinder having substantially the same volumetric capacity, a crank shaft, a

connecting rod connecting the pump piston with the crank shaft, and a partition member receiving and participating in the oscillatory movement of the connecting rod and forming a closure for the adjacent end of the pump cylinder.
